CLAIM

The ornamental design for a storage box, as shown and described.

DESCRIPTION

FIG. 1 is a perspective view of a storage box showing the new design;

FIG. 2 is another perspective view thereof;

FIG. 3 is a left side elevation view thereof;

FIG. 4 is top plan view thereof; and,

FIG. 5 is an enlarged view of the encircled portion in FIG. 1.

The dash-dot-dash lines in FIG. 1 and FIG. 5 illustrate the enlarged view indicators and form no part of the claimed design.

The equal length broken lines depict portions of the storage box that form no part of the claimed design.

1 Claim, 5 Drawing Sheets
